(57) **CLAIM**

The ornamental design for an electrical connector, as shown and described.

DESCRIPTION

FIG. 1 is a front, top and left-side perspective view of an electrical connector showing our new design;

FIG. 2 is a front, bottom and right-side perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged cross-sectional view taken in the direction of line 9-9 in FIG. 8;

FIG. 10 is an enlarged cross-sectional view taken in the direction of line 10-10 in FIG. 8; and,

FIG. 11 is another front, top, and left side perspective view thereof shown in environment.

The evenly spaced broken lines depict environment in the additional broken line structure shown in the FIG. 11 view and depict portions of the electrical connector, in the FIGS. 1-8 and 11 views, that form no part of the claimed design. Also, the evenly spaced broken lines in the FIG. 9 and FIG. 10 views depict the surfaces at the cut marks and form no part of the claimed design. The single dot dash broken lines define the boundary of the claimed design and form no part of the claimed design.
